JOHN H. WILHELM, OF ROCKAWAY BEACH, NEW YORK, ASSIGNOR TO MARKON MANUFACTURING CO. INC., OF NEW YORK, N. Y., A CORPORATION OF NEW YORK

EYE SET FOR DOLLS

Application filed January 19, 1928. Serial No. 247,764.

This invention relates to an eye set for dolls and similar manikins, and relates more particularly to improvements in animated or self-moving eyes for dolls and the like.

5 The prime desideratum of my present invention centers about the provision of an improved eye set of the animated type in which the movement of the eye set between eye opening and eye closing positions is controlled by the usual movement of the doll's head between erect and recumbent positions, combined with a secondary movement which is imparted to the doll's head by the child. The secondary movement and the operation of 10 the eye set thereby is designed to simulate a more natural or lifelike behaviour of the doll and to reproduce the care and actions of a solicitous mother characteristic of the act of "putting" an infant to sleep and the act of 15 20 waking an infant from sleep.

To accomplish this desideratum, it is the prime object of my invention to provide an improved eye set of the type which is movable in response to a movement of the doll 25 between erect and recumbent positions in which means are provided for checking or preventing a closing movement of the eye members of the eye set until the doll has been turned to one side of a recumbent or lying 30 position, and for checking or preventing the return or opening movement of the eye members until the doll is shook or gently vibrated as if in response to a coaxing or waking ac- 35

tion.

35 A further principal object of the invention centers about the provision of an improved doll's eye set in which the checking means for preventing or retarding either the opening or closing movements of the eye members is 40 mounted on or connected to the supporting carrier for the eye members so that all of the parts forming the eye set are adapted to be assembled as a unit for facility of handling and for ease of mounting the same in the 45 doll's head.

Further prime objects of the invention re- 45 side in the provision of an improved eye set of the character hereinbefore set forth in which the parts are coordinated for produc- 50 ing the desired functions with simplicity and

precision, with said parts so structurally arranged and organized as to permit the eye set to be manufactured in quantity production with ease and at a comparatively low cost.

To the accomplishment of the foregoing 55 and such other objects as will hereinafter appear, my invention consists in the elements and their relation one to the other, as hereinafter more particularly described and sought to be defined in the claims, reference 60 being had to the accompanying drawings which show the preferred embodiments of my invention, and in which

Fig. 1 is a perspective view of a doll's head in a recumbent position and showing the eye set of my present invention in mounted position therein, and showing the operational 65 characteristics thereof,

Fig. 2 is a view taken in cross section in the plane of the line 2—2, Fig. 1 and showing the doll's head in vertical or erect position, 70

Fig. 3 is a rear elevational view thereof,

Fig. 4 is a top plan view of the eye set shown detached from the doll's head with parts shown in section, 75

Fig. 5 is a rear elevational view of an eye set showing a modification of my invention,

Fig. 6 is an elevational view thereof taken in cross section in the plane of the line 6—6, 80 Fig. 5,

Fig. 7 is a rear elevational view of a modified form of eye set showing the manner of applying my invention thereto, and

Fig. 8 is a side elevational view of the eye set shown in Fig. 7. 85

Referring now more in detail to the drawings and having reference first to Figs. 1 to 4 thereof, the improved eye set of my present invention comprises generically a carrier generally designated as A attachable interiorly 90 to a doll's head 10, eye members and a holder generally designated as B movably mounted on the carrier A, a means generally designated as C connected to the eye members for moving the same between open and closed positions, combined with a means generally designated as D operative for checking the closing movement of said eye members until the head 95 has been turned to one side, the said means D being preferably also effective for checking 100

the return or opening movement of the eye members until a gentle vibration is imparted to the doll's head 10 in response to a simulating coaxing or waking action.

- 5 In the preferred form of the invention, as shown for example in Figs. 1 to 4 of the drawings, the carrier A, the holder and eye members B, the means C which preferably comprises the usual pendulous or weighted member operative for moving the eye members between their closed and open positions and the checking means D are combined and organized to form a composite unit adapted to be assembled as an entity, as clearly shown 10 in Fig. 4 of the drawings, so that the same may be handled with facility and mounted with convenience and ease in the doll's head, as clearly shown in Figs. 1 to 3 of the drawings.
- 15 20 The carrier A is preferably of the type embodying attaching means which may be impaled under pressure into one or more walls of the doll's head for anchoringly mounting the eye set in the head; and in 25 Figs. 1 to 4 of the drawings I show a carrier of the general type disclosed, for example, in the patent to A. Konoff, 1,621,072 of March 15, 1927. This type of carrier comprises a body 11 made of sheet metal, the top and bottom edges of which are bent or turned to provide channels, in which channels attaching members 12 and 13 are longitudinally slidable with a close or tight fit. The attaching members are provided with the terminal tangs 14, 30 35 14 which are impaled or embedded in the opposite cheek walls of the doll's head 10, as most clearly shown in Fig. 3 of the drawings, when the attaching members 12 and 13 are forced outwardly in opposite directions, this 40 being effected by means of a suitable tool which engages in orifices 15 and 16 provided in the attaching members. Preferably the attaching members may be provided with the stop or limiting fingers 17 and 18 formed integrally with the attaching members.
- 45 50 55 The carrier A is provided with a support for mounting or journaling the eye holder B, and preferably this support is arranged in a medial plane of the doll's head and medially of the carrier A. This support is desirably formed integrally with the body 11 of the carrier by striking up therefrom a pair of bifurcated arms 19, 19, in the forks of which the eye holder B is mounted for oscillatory movement, as most clearly shown in Figs. 1, 2 and 4 of the drawings.

55 60 65 The eye holder B in the form of the invention shown in Figs. 1 to 4 of the drawings, preferably comprises a cross rod 20 forming a bridge piece oscillatably receivable between the tines of the bifurcated arms 19 and a pair of eye members 21 and 22 mounted on said cross rod and adjustably spaced thereon to fit into eye sockets 23 of the doll's head when the 70 75 80 85 eye set is fitted into the doll's head. The type

of eye holder and eye member adjustment which I prefer to use is that disclosed in detail in the patent to Samuel Marcus, 1,601,133 of September 28, 1926.

As heretofore set forth, it is a desideratum of the invention to control the eye opening and closing movements of the eye members by the usual movement of the doll's head between erect and recumbent positions, combined with a secondary movement which is 70 75 80 85 90 95 100 imparted to the doll's head by the child. The means controlled by the secondary movement is designed so as to be preferably associated with both the act of "putting" the doll to sleep and the act of waking the doll; and said means is designed and constructed so as to prevent a closing movement of the eye members until the doll's head is turned or laid to one side of a recumbent position, and so as to prevent a return or opening movement of the eye members until a gentle shock or vibration is imparted to the doll, these movements simulating the solicitous care and natural behaviour of both mother and child.

To accomplish these objects I provide the weighted or pendulous member C comprising a rod 24 supporting at its bottom a weight 25, the said rod being attached or connected to the cross rod 20, the connecting means comprising an element 26 fixed centrally to the rod 20 as by brazing or welding, to which element the upper end of the rod 24 is swiveled as by means of the eyelet 27. Cooperating with this swivelly mounted pendulum C, I provide the checking means D in the form of an arcuate shaped member 28 which is fixedly attached to the carrier A medially thereof, the said member 28 being provided integrally for this purpose with an attaching means 29 having fingers 30 and 31 which straddle the body 11 of the carrier and are turned over into tight frictional engagement therewith, as clearly shown in Figs. 2 to 4 of the drawings.

The cooperation between the pendulum C and the checking means D is such that when the eye members 21 and 22 are in open position and the doll's head 10 is moved from an erect to a horizontal position, the bottom edge 32 of the checking means D serves to 110 115 120 125 act as a stop against which the rod 24 of the pendulum abuts, as most clearly shown in Figs. 2 and 4 of the drawings, this preventing the closing movement of the eyes, the eyes remaining open as shown in Fig. 2 of the drawings. When, however, the doll's head 10 is then moved or tilted to one side or the other of the recumbent position sufficient to permit a movement of the pendulum rod 24 laterally of the longitudinal plane in which the pendulum normally lies, the pendulum rod 24 will swing clear of the checking means D and will then be free to move to the dotted line position shown in Fig. 2 of the drawings, causing the eye members to move to their 130

closed position. When the doll is then returned from a tilted to a normal lying position, the pendulum C will move toward the medial plane and the rod 24 thereof will be engaged by one of the shoulders 33, 33 formed in the upper part of the arcuate check plate 28 so that when the doll is returned to the non-sleeping or erect position, the doll's eyes will remain closed, as clearly shown in Fig. 2 of the drawings, until a light shocking or vibratory movement is imparted to the doll's head sufficient to dislodge the pendulum rod 24 from the stop shoulder 33; and when so dislodged, the eye members under the influence of the pendulum moving from the full line position shown in Fig. 2 to the dotted line position shown therein will then move from the closed to the open position.

In Figs. 5 and 6 of the drawings I show a modified form of the invention in which the checking means is constructed to guide the movement of the pendulum between open and closed positions, the checking means being further designed and constructed to provide a positive stop or check for the eye moving means in closed position when the doll remains in a tilted recumbent position. Otherwise the eye set shown in Figs. 5 and 6 of the drawings is of the same construction as that shown in Figs. 1 to 4 of the drawings and is designated by similar and primed reference characters. The checking means D' is different, however, and comprises an arcuate shaped plate 35 which may be soldered to the body member 11' of the carrier A' along the top edge 36 of said plate, the said plate being provided with the cam slots 37 and 38 arranged symmetrically on opposite sides of the medial or longitudinal plane of the eye set. These cam slots form or define guiding means for the pendulum rod 24' and terminate at their tops in enlargements which provide stop shoulders 39, 39 on opposite sides of each cam slot the said cam slots being joined in the medial plane of the carrier by a stop shoulder 40. With this construction it will be apparent that when the doll's head is moved from the vertical to the horizontal, the pendulum will be checked in a manner similar to that heretofore described in connection with Figs. 1 to 4 of the drawings, but when the doll's head is tilted or moved to either side, the pendulum, free to swing laterally of the normal longitudinal plane thereof, will move guided by one or the other of the cam slots 37 and 38 to impart a closing movement to the eye members. It will be further apparent that at the end of its movement the pendulum rod 24' will be lodged on either side of one of the cam slot enlargements, and engaged by a stop shoulder 39 will be prevented or checked against return movement until a slight shock is imparted to the doll's head. While I have shown a stop shoulder on both sides of a slot 37 it will be

manifest that in some cases it is desirable only to have one such stop shoulder.

In the manufacture of the eye set, the carrier A' with its attached checking means D' is made separate from the eye holder B' with its attached pendulum C'; and to permit convenient assembly of these parts, the arcuate plate 35 of the checking means D' is slotted at 41 sufficient to permit the parts 42 and 43 of the plate 35 to be sprung apart to allow the insertion of the pendulum rod 24'. In lieu of soldering the plate 35 along the edge 36, the said plate may be formed integrally with an attaching member 44 having a construction and a manner of attachment similar to the attaching member 29 heretofore described in connection with Figs. 1 to 4 of the drawings.

In the modification of the invention shown in Figs. 7 and 8 of the drawings, the stop or checking means D² comprises an arcuate plate having a design and construction substantially similar to that described in connection with Figs. 5 and 6 of the drawings, the said plate having a finger 45 which may be connected as by spot welding to a carrier A² of a type which may be attached to a part of the doll's head intermediate the eye sockets thereof. In this form of construction the eye members 46 and 47 oscillatably carried on a cross rod 48 are connected to two arms 49 and 50 of a substantially U-shaped frame 51, which frame swivelly carries as at 52 the pendulous member C². The rod 53 of the pendulous member C² comprises in effect a lever having an application arm 54 which is guided for movement in the cam slots 55 and 56 of the checking means D².

The form of carrier A² shown in this modified form of the invention comprises a bifurcated support for the cross rod 48, which cross rod is loosely mounted in the support and acted upon by a spring 57 housed by the carrier A², the said carrier having terminal tangs 58 and 59 which are adapted to be moved in opposite directions to be impaled or embedded into stud walls forming part of the doll's head (not shown). In this form of the invention it will be seen that the carrier A² and the check plate D² also form a unit relative to which the eye members 46 and 47 and the pendulum C² are movable, the checking means D² cooperating with the pendulum C² to control the eye opening and closing movements of the eye members in response to a secondary movement imparted to the doll's head and similar to that described in connection with the preceding figures.

The manner of making and using the improved eye set of my present invention and the many advantages thereof will, in the main, be fully apparent from the above detailed description thereof. It will be apparent, for example, that in all of the preferred forms of the invention, all of the parts

of the eye set are assembleable into a single unit or entity for facility of handling, assembling and mounting in the doll's head. It will be further apparent that the unitary construction and the assembly provided permits the functional interrelation between the parts to be predetermined by the manufacture of the eye set, and hence results in the making of eye sets of this character which may be operated with exactness and reliability. Other advantages will be readily apparent to those skilled in the art of designing eye sets intended for manufacture in quantity production at reduced costs.

It will also be apparent that while I have shown and described my invention in the preferred forms, many changes and modifications may be made in the structure disclosed without departing from the spirit of the invention, defined in the following claims.

I claim:

1. An eye set for a doll's head comprising a carrier, eye members movably mounted on the carrier, means connected to the eye members for moving the same between open and closed positions, and means on said carrier for normally checking the closing movement of said eye members and for permitting free closing movement of said eye members when the head has been turned to one side.

2. An eye set for a doll's head comprising a carrier embodying means for attaching the carrier to the doll's head, eye members movably mounted on the carrier, means attached to the eye members for moving the same between open and closed positions, and means attached to said carrier for normally checking the closing movement of said eye members and for permitting free closing movement of said eye members when the head has been turned to one side.

3. An eye set for a doll's head comprising, a carrier having a support arranged medially thereof, a cross rod having eye members spaced thereon movably mounted on said support, means connected to the eye members for moving the same between open and closed positions, and means on said carrier for normally checking the closing movement of said eye members and for permitting free closing movement of said eye members when the head has been turned to one side.

4. An eye set for a doll's head comprising a carrier, an eye member holder movably mounted on the carrier, means connected to the eye member holder for moving the same between open and closed positions, and means on said carrier for normally checking the closing movement of said eye members and for permitting free closing movement of said eye members when the head has been turned to one side, said carrier, holder and both of said means being assembled as a unit for handling and for mounting in the head.

5. An eye set for a doll's head comprising a carrier, eye members movably mounted on the carrier, means connected to the eye members for moving the same between open and closed positions, means on said carrier for automatically checking the closing movement of said eye members until the head has been turned to one side, and means on said carrier for automatically checking the return opening movement of said eye members until a shock is imparted to said head.

6. An eye set for a doll's head comprising a carrier, eye members movably mounted on the carrier, means connected to the eye members for moving the same between open and closed positions, means for automatically checking the closing movement of said eye members while the head looks upward, but permitting the closing movement when the head is turned to look toward one side, and means for automatically checking the opening movement of said eye members until a shocking motion is imparted to said head.

7. An eye set for a doll's head comprising a carrier, eye members movably mounted on the carrier, means connected to the eye members for moving the same between open and closed positions, and means stationarily mounted in said head for automatically checking the closing movement of said eye members while the head looks upward, but permitting the closing movement when the head is turned to look toward one side and for checking the opening movement of said eye members until a shocking motion is imparted to said head.

8. An eye set for a doll's head comprising a carrier, eye members movably mounted on the carrier, means connected to the eye members for moving the same between open and closed positions, and means stationarily mounted in said head for automatically checking the closing movement of said eye members until the head has been turned to one side, and for then permitting free and uncheck closing movement of said eye members.

9. An eye set for a doll's head comprising, a carrier having attaching means for attaching the carrier to the doll's head, eye members movably mounted on the carrier, means connected to the eye members for moving the same between open and closed positions, and means stationarily mounted on the doll's head for automatically checking the closing movement of said eye members while the head looks upward, but permitting the closing movement when the head is turned to look toward one side, and means also stationarily mounted in the doll's head for checking the opening movement of said eye members until a shocking motion is imparted to said head.

10. An eye set for a doll's head comprising a carrier, eye members movably mounted on the carrier, a pendulum connected to the eye

members for operating the same between open and closed positions, said pendulum being mounted for an independent lateral movement, and means on said carrier for checking the operating movement of said pendulum until the head has been turned to one side to permit a lateral movement of said pendulum and for then permitting free operating movement of said pendulum.

5 11. An eye set for a doll's head comprising a carrier, eye members movably mounted on said carrier, a pendulum connected to the eye members and arranged to swing in a longitudinal plane of the doll's head for moving the eye members between open and closed positions, said pendulum being mounted for an independent movement laterally of said longitudinal plane, and means on said carrier arranged in said longitudinal plane for 15 checking the operating movement of said pendulum until the doll's head has been turned to one side to permit the pendulum to move laterally of said longitudinal plane.

12. An eye set for a doll's head comprising a carrier having a support arranged medially thereof, eye members movably mounted on said medially arranged support, a pendulum connected to the eye members and arranged to swing in a medial plane of the doll's head for moving the eye members between open and closed positions, said pendulum being mounted for an independent movement laterally of said medial plane, and means on said carrier arranged in said medial plane 30 for checking the operating movement of said pendulum until the doll's head has been turned to one side to permit the pendulum to move laterally of said medial plane.

13. An eye set for a doll's head comprising a carrier, eye members movably mounted on said carrier, a pendulum connected to the eye members and arranged to swing in a longitudinal plane of the doll's head for moving the eye members between open and closed 45 positions, said pendulum being mounted for an independent movement laterally of said longitudinal plane, and means arranged in said medial plane for automatically checking the operating movement of said pendulum until the doll's head has been turned to one side to permit the pendulum to move laterally of said medial plane and for then permitting free and unchecked closing movement of said eye members.

55 14. An eye set for a doll's head comprising a carrier, eye members movably mounted on the carrier, a pendulum connected to the eye members for operating the same between open and closed positions, and means wholly on said carrier cooperating with said pendulum to check a closing movement thereof while the head looks upward, but permitting the closing movement when the doll's head is turned to look toward one side, 60 to guide the movement of said pendulum be-

tween eye opening and closing positions and to check an opening movement of said pendulum until a shocking motion is imparted to said head.

15. An eye set for a doll's head comprising a carrier, eye members movably mounted on the carrier, a pendulum connected to the eye members for operating the same between open and closed positions, said pendulum being mounted on said eye members for an independent lateral movement, and a cam plate on said carrier cooperating with said pendulum and embodying a stop means to check a closing movement of the pendulum until the doll's head has been turned to one side to move said pendulum laterally, a cam slot to guide the movement of said pendulum between open and closed positions and a stop means to check an opening movement of said pendulum until a shocking motion is imparted to said head.

16. An eye set for a doll's head comprising a carrier, eye members and an element connecting the eye members movably mounted on the carrier, a pendulum pivotally connected to said connecting element, said pendulum being movable with said element to move the eye members between open and closed positions and being pivotally movable relatively to said element, and a cam plate on said carrier cooperating with said pendulum and embodying a stop means to check an eye closing movement of the pendulum until the doll's head has been turned to one side to permit a pivotal movement of said pendulum.

17. An eye set for a doll's head comprising a carrier having a centrally arranged support, eye members movably mounted on the carrier support, a pendulum connected to the eye members for operating the same between open and closed positions, said pendulum being pivotally mounted on said eye members for an independent lateral movement, and a cam plate on said carrier cooperating with said pendulum, said cam plate embodying a stop means at one end to check a closing movement of the pendulum until the doll's head has been turned to one side to permit a pivotal movement of said pendulum, a cam slot to guide the movement of said pendulum between open and closed positions and a stop means on both sides of said slot at the other end of the plate to check an opening movement of said pendulum until a shocking motion is imparted to said head.

Signed at New York, in the county of New York and State of New York, this 16th day of January A. D. 1928.

JOHN H. WILHELM.
